UNITED STATES PATENT OFFICE.

GEORGE STOCKINGER, OF LOS ANGELES, CALIFORNIA.

TOOL-CASE.

953,930.

Specification of Letters Patent.

Patented Apr. 5, 1910.

Application filed April 17, 1909. Serial No. 490,547.

To all whom it may concern:

Be it known that I, GEORGE STOCKINGER, a citizen of Austria, residing at Los Angeles, in the county of Los Angeles and State of California, have invented new and useful Improvements in Tool-Cases, of which the following is a specification.

This invention relates to a pocket case for carrying tools, and more particularly various sized drills used by craftsmen, and an object thereof is to provide a suitable case that may be conveniently carried in the pocket of the workman, and in which the drills may be properly classified and of easy access.

15 A further object is to provide a case, whereby the drills disposed therein will be held securely against accidental displacement.

I accomplish these objects by means of the 20 device described herein and shown in the accompanying drawings, in which:—

Figure 1—is a perspective view of my improved drill case. Fig. 2—is a face view of the case in open position, parts being broken 25 away for clearness of illustration. Fig. 3—is an end view of the case in an open position, portions being broken away for clearness of illustration.

In the embodiment of my invention illustrated in the accompanying drawing, 5 designates a pair of rectangular members, preferably formed of wood, the two adjacent edges being joined together by a flexible member or back 6, preferably formed of 35 leather to resist wear. The inner oppositely disposed edges of members 5 are provided with a series of transverse bores 7 therein for the reception of the various sized drills 8. The oppositely disposed edges adjacent each 40 bore 7 is supplied with a series of numbers corresponding to the size of the various

drills. The inner faces of members 5 can be supplied with different tables and information relating to drillings. Each member 5 on its oppositely disposed edges is provided 45 with a longitudinal saw-kerf 9 that will furnish the edges with enough resiliency to prevent the drills from falling out of the bores when carrying the drill case in the pocket.

It will be apparent from the above description that I have provided a novel drill case, whereby drills of various sizes may be carried therein, properly classified, and of convenient access to the workman.

Having described my invention what I 55 claim as new and desire to secure by Letters Patent is:—

1. A pocket drill case, comprising two flat rigid tool holders provided with transverse bores in their oppositely disposed edges for 60 the reception of drilling tools, and a strip of flexible material connecting the oppositely disposed edges of the rigid holders, whereby when the inner faces of the holders are brought into contact the flexible connecting 65 strip will act as a protective covering for the tools projecting from the holders.

2. A pocket tool case, comprising two rigid members provided with transverse bores in their oppositely disposed edges, each of said 70 members on their oppositely disposed edges being provided with a centrally disposed longitudinal slot, and a flexible member connecting the two rigid members.

In witness that I claim the foregoing I 75 have hereunto subscribed my name this 9th day of April, 1909.

GEORGE STOCKINGER.
